UNITED STATES PATENT OFFICE.

CHARLES RAUCH, OF ST. LOUIS, MISSOURI, ASSIGNOR TO TWINPLEX SALES COMPANY,
COMPOSED OF HERBERT S. GARDNER, OF ST. LOUIS, MISSOURI.

RAZOR-BLADE SHARPENER.

1,265,956.

Specification of Letters Patent.

Patented May 14, 1918.

Application filed March 29, 1915. Serial No. 17,579.

To all whom it may concern:

Be it known that I, CHARLES RAUCH, a citizen of the United States, residing at St. Louis, in the county of St. Louis City and State of Missouri, have invented certain new and useful Improvements in Razor-Blade Sharpeners, of which the following is a specification.

A leading object of the present invention 10 is the production of a razor blade or similar sharpener or stropper having oscillatory sharpening elements and a shiftable blade-holder, whether for double-edged or single-edged blades, manipulated by a handle adapted to be turned in one direction only to automatically oscillate the sharpeners in opposite directions and rock or shift the blade-holder in proper timed relation to the movements of the other parts to secure 20 the desired sharpening or stropping functions, the construction including simple and effective means for accomplishing these results, which instrumentalities may be easily manipulated and are economical to manufacture, being also unlikely to become de-ranged or damaged in operation.

In order that those skilled in this art may have a full understanding of the invention, preferred embodiments of the same have 30 been illustrated in the accompanying drawings forming a part of this specification, and throughout the various views of which like reference characters refer to the same parts.

In these drawings,

35 Fig. 1 is a side view of one embodiment of the invention;

Fig. 2 is a vertical section on line 2—2 of Fig. 4;

40 Fig. 3 is a vertical section on line 3—3 of Fig. 4;

Fig. 4 is a plan view of the device;

Fig. 5 is a vertical cross-section on line 5—5 of Fig. 4;

45 Fig. 6 is a perspective view of one of the blade-holders adapted to receive a single-edge blade;

Fig. 7 illustrates the blade-holder open;

Fig. 8 shows the rack operated by the handle for oscillating the stropping elements 50 and manipulating the blade-holders;

Fig. 9 is a side view of a similar structure adapted to sharpen double-edged blades;

Figs. 10 and 11 are views of a double-edged blade-holder and the associated blade. 51

Fig. 12 illustrates in section the ratchet connection of the operating-handle with the crank-shaft, and

Fig. 13 illustrates another clutch-connection between the operating-handle and the 60 crank-shaft.

Referring first to the device illustrated in Figs. 1 to 8, inclusive, it will be observed that the structure comprises an open-top metal shell or casing 20 equipped with a 65 partition or wall 21 having a horizontal flange 22 forming a top or cover for the smaller of the two compartments into which the wall divides the casing. Three cylindrical stropping or sharpening elements 70 23, 24 and 25, are accommodated in the larger of these compartments, and are fixedly mounted on their respective shafts 26, 27 and 28, having suitable bearings in the wall 29 of the casing and in the partition 75 wall 21. As is customary in devices of this kind, these cylindrical stropping elements are covered with leather or other suitable sharpening or stropping material. Each of such shafts projects through the wall 21, 80 and in the smaller of the compartments of the casing they are equipped with gears or pinions 30, 31 and 32, respectively.

An apertured bar or plate 33 is slidingly mounted in the casing, and has integral 85 therewith or fastened thereto, on one side, an inverted rack 34, the teeth of which are in mesh with those of all of the three pinions, as illustrated in Fig. 2, the bar and rack being of less length than the interior 90 of the stropper-casing to permit its reciprocation, the rack being of such length that at no time are its teeth out of mesh with any of the three pinions.

The device is equipped with a shaft 35 95 having a bearing in the wall 26 of the casing, the protruding end of the shaft being provided with a handle 37 having a ratchet connection 38, of any suitable construction, with the shaft, which permits the handle 100 to turn the shaft in a clockwise direction, the handle turning freely on the shaft if revolved counter-clockwise. The inner end of the shaft has a crank arm 39 thereon, provided with a crank pin 40 engaging a 105 slot 41 of bar 33. Obviously, therefore, as

the handle is revolved in a clockwise direction, the crank will cause the reciprocation of the rack, and this in turn will effect the simultaneous oscillation of all of the cylindrical stropping elements.

These stroppers are spaced apart as shown in the various figures, and in such spaces oscillatory blade-holders are employed, two being used in the present instance with the three stroppers. Each of such blade-holders is adapted to accommodate a single-edge blade, and comprises a bar 42 with a journal 43 at its rear end, received and rotatable in a bearing in the casing-wall 29. At its other end, the bar 42 has another journal 44 accommodated in a bearing 45 in the front wall of the casing. At 46, bar 42 has hinged thereto a companion bar 47 equipped with a bent handle 48 by which it may be manipulated, and supplied also with a bent arm 49 at one end adapted to take over the bar 42 to securely hold them together. This bar may be shaped to accommodate any particular style or form of razor-blade, the structure differing in minor details with different well known makes of blades. In the present instance, the blade 50 has end shoulders 51, 51 adapted to bear against coöperating shoulders 52, 52 provided on bar 47, and in order to maintain the blade properly in position, its back or upper edge 53 engages a bent lug 54. As is clearly shown in Fig. 6, when the two bars 42 and 47 are brought together, the blade is rigidly and firmly held therein without possibility of dislodgment.

Bar 42 is also supplied with a depending leaf-spring 55 and a cam rider 56 of somewhat pointed conformation, as shown in Figs. 2 and 3. It should be observed that both the plate or bar 33 and its associated rack 34 are equipped with two apertures 57 and 58 of the shape shown in Figs. 2 and 8; that is to say, each of these apertures has a flat side 59 with recesses 60 and 61 at its opposite ends, such recesses, of course, forming portions of the main aperture. As is perhaps shown more clearly in Figs. 2 and 5, the cam riders 56 of the two blade-holders are accommodated in the apertures 57 and 58, the surfaces 59 being adapted to bear on such riders so as to properly press the blades of the blade-holders against the revolving stropping elements. The partition wall 21 is also apertured at 62 and 63 for the accommodation of the blade-holders, and the leaf springs 55 are adapted to engage the opposite walls of such apertures, as shown in Fig. 3.

The operation of this appliance takes place practically as follows:

Assuming that the two blade-holders have been supplied with a pair of single-edge blades 50, 50, and that the handle 37 is being rotated in a clockwise direction, then the

plate 33 and its associated rack 34 are moving toward the left as the parts are viewed in Fig. 2, the edges of the blades being held against the cylindrical sharpening surfaces of the two stroppers 24 and 25 by reason of the engagement of the surfaces 59 with the riders 56, as is clearly shown in Fig. 2. Under these circumstances, the two springs 55 are held somewhat bowed and under flexure against the walls of the apertures 62 and 63. At just ~~about~~ the time the crank 39 reaches dead center, the surfaces or tracks 59 pass beyond the cam riders 56, and the blade-holders, under the straightening action of their springs 55, swing clockwise slightly, so that as the handle continues its rotation and the rack moves to the right, the surfaces 59 will then engage the opposite surfaces of the riders 56, rocking the blade-holders, so that the blades will then coact with the two stroppers 23 and 24, which are now revolving in the opposite direction. Such coaction of the surfaces 59 and the riders holds the blades firmly under their own spring pressure against the stropping surfaces, and also holds the springs 55 bowed in the opposite direction against the opposite edges of the recesses 62 and 63, so that when the rack reaches the limit of its right-hand movement, these springs will rock the blade-holders sufficiently whereby during the next stroke of the rack the blades will engage the other pair of stroppers. It will be observed, of course, that the cavities 60 and 61 permit this slight rocking of the holders under the action of springs 55 during the reversal of rotation of the stroppers. There is consequently no danger of cutting the stroppers by the blade-edges, the blade-holders being automatically rocked so as to properly engage the sharpening elements under all circumstances. Stated somewhat differently, the stroppers oscillate, and the blade-holders are rocked in proper timed relation to effect efficiently the proper stropping functions.

The number of stroppers and the number of blade-holders is, of course, immaterial. That is to say, the number illustrated might be either increased or decreased. But for each single-edge blade, one side of its edge is sharpened by one stropper, and the other side by a companion stropper.

If it were not for the presence and action of the springs 55, the blade-holders might not rock sufficiently when released to be still further rocked positively in the right direction by the coöperation of their riders with the sliding surfaces of the rack bar. These springs, in straightening out, right the blade-holders sufficiently so that their riders will be properly engaged to effect the rocking movement.

In Figs. 9, 10 and 11, I have illustrated a

modification of the invention, showing the same applied to a device for sharpening double-edged blades, the structure being equipped with means for quickly opening the blade-holder for the withdrawal of a sharpened blade and the insertion of one to be acted upon. In this case, the stroppers, their gears, the rack, the handle, and the crank connection between the handle and the rack, together with the apertures of the rack-bar and the co-operating blade-holder riders are all constructed as in the other device. In this instance, however, the blade-holder consists of two spring arms 70 and 71, which, under their spring action, tend to separate, but which are fastened together at one end by a rivet 72. One of these bars 71 is deformed or pressed to provide a pair of lugs 73, 73, adapted to be accommodated in the apertures of the double-edged blade 74. The companion bar 70 is also pressed or deformed to provide recesses 75, 75 for the accommodation of such lugs 73. The bar 70 has a slotted yoke 76 adapted to fit over the bar 71, and it also has a pair of fingers 77, 77 engaging the under surface of the companion bar 71, these parts co-operating so as to maintain the two bars of the holder in proper register. One end of the holder has a journal 78 corresponding to the journal 44 of the other holder of Fig. 6, and at its opposite end this double-edged blade-holder has a split journal 79 adapted to project through an aperture 80 of the rear wall of the shell or casing. As in the previous instance, this blade-holder has a depending leaf-spring 81 performing the same function as the spring 55 of the other style of holder, and it also has a cam or beveled rider 82 acting in the same manner as the corresponding rider of the other form of blade-holder.

For each of these blade-holders, the rear wall of the shell has pivoted thereto at 83 a latch 84 having an operating handle 85 and a hook-shaped portion 86 adapted to fit over the protruding end of the split journal 79 and maintain the holder in proper position, acting as a portion of the bearing for such journal. This latch 84 has a wedge tooth 87 adapted when the latch is swung upwardly around its pivot to enter between the bars 70 and 71, spreading them apart to facilitate the withdrawal of the blade and the insertion of another.

The sharpening operation of this modified structure is substantially the same as that of the other device except that in this instance both edges of each double-edged blade are being stropped simultaneously, the one side of one edge on the one stropper, and the opposite side of the same edge on the next adjacent stropper after the blade-holder has been rocked. Stated somewhat differently, each of the blades, except during

the shifting of the blade-holder, has one side of one edge engaging one stropper, and the opposite side of the other edge in sharpening engagement with the next adjacent stropper. Then, when the blade-holder is rocked, the other side of the first edge contacts with the second stropper, and the other side of the other edge engages the first-mentioned stropper. As in the previous instance, the stroppers are oscillated automatically and the blade-holders similarly rocked by merely turning the handle always in the one direction.

To those skilled in this art, it will be clear that the invention is susceptible of a variety of other embodiments, and that various minor mechanical changes may be made in those illustrated and described without departure from the substance of the invention and without the sacrifice of any of its substantial benefits and advantages; but it is believed that the essential features of the invention can be readily understood from the two embodiments herein set forth.

In this application I have described the rotation of the operating-handle as occurring in a clockwise direction, as this is the more natural way in which it would ordinarily be rotated. It should be obvious, however, that the device can be actuated equally well if the handle is rotated in a counter-clockwise direction, provided the clutch or ratchet mechanism between the handle and its shaft is correspondingly modified. In Fig. 13 I have illustrated such a modification wherein the pawl clutch connection 38^a between the handle and the crank-shaft permits an operative connection of the handle with the shaft when the former is rotated counter-clockwise, but permits the handle to rotate freely on the shaft when revolved clockwise.

I claim:

1. In a sharpening appliance of the character described, the combination of a pair of oscillatory sharpening elements, a movable blade-holder having a rider, a reciprocatory bar, a handle, an operative connection between said handle and bar to reciprocate the latter, actuating means connecting said bar and elements to oscillate the latter by the reciprocation of the former, and means on said bar co-acting with said rider to hold the blade in the blade-holder against said sharpening elements, substantially as described.

2. In a sharpening appliance of the character described, the combination of a pair of oscillatory sharpening elements, a movable blade-holder having a rider, a reciprocatory bar, a handle, an operative connection between said handle and bar to reciprocate the latter, actuating means connecting said bar and elements to oscillate the latter by the reciprocation of the former, means on said bar

- co-acting with the rider to hold the blade in the blade-holder against said sharpening elements, and means to shift the blade-holder at each change of direction of rotation of said elements, substantially as described.
5. 3. In a sharpening appliance of the character described, the combination of a pair of oscillatory sharpening elements, a movable blade-holder having a rider, a reciprocatory bar, a handle, an operative connection between said handle and bar to reciprocate the latter, actuating means connecting said bar and elements to oscillate the latter by the reciprocation of the former, means on said bar co-acting with said rider to hold the blade in the blade-holder against said sharpening elements, and spring means to shift the blade-holder at each change of direction of rotation of said elements, substantially as described.
10. 4. In a sharpening appliance of the character described, the combination of a pair of oscillatory sharpening elements, a pivoted oscillatory blade-holder having a rider, a reciprocatory bar, a handle, an operative connection between said handle and bar to reciprocate the latter, actuating means connecting said bar and elements to oscillate the latter by the reciprocation of the former, and means on said bar co-acting with said rider to hold the blade in the blade-holder against the sharpening elements, substantially as described.
15. 5. In a sharpening appliance of the character described, the combination of a pair of oscillatory sharpening elements, a pivoted oscillatory blade-holder having a rider, a reciprocatory bar, a handle, an operative connection between said handle and bar to reciprocate the latter, actuating means connecting said bar and elements to oscillate the latter by the reciprocation of the former, and means on said bar co-acting with said rider to hold the blade in the blade-holder against the sharpening elements, substantially as described.
20. 6. In a sharpening appliance of the character described, the combination of a pair of oscillatory sharpening elements, a pivoted oscillatory blade-holder having a rider, a reciprocatory bar, a handle, an operative connection between said handle and bar to reciprocate the latter, actuating means connecting said bar and elements to oscillate the latter by the reciprocation of the former, means on said bar co-acting with said rider to hold the blade in the blade-holder against the sharpening elements, substantially as described.
25. 7. In a sharpening appliance of the character described, the combination of a pair of oscillatory sharpening elements, a pivoted oscillatory blade-holder having a rider, a reciprocatory bar, a handle, an operative connection between said handle and bar to reciprocate the latter, actuating means connecting said bar and elements to oscillate the latter by the reciprocation of the former, means on said bar co-acting with said rider to hold the blade in the blade-holder against the sharpening elements, and means to rock said blade-holder at each change of direction of rotation of said elements, substantially as described.
30. 8. In a sharpening appliance of the character described, the combination of a pair of oscillatory sharpening elements, a pivoted oscillatory blade-holder having a rider, a reciprocatory bar, a handle, an operative connection between said handle and bar to reciprocate the latter, actuating means connecting said bar and elements to oscillate the latter by the reciprocation of the former, means on said bar co-acting with said rider to hold the blade in the blade-holder against the sharpening elements, and means to shift the blade-holder at each change of direction of rotation of said elements, substantially as described.
35. 9. In a sharpening appliance of the character described, the combination of a plurality of sharpening elements, a gear for each of said elements, a rack meshing with said gear, a rotatable handle, a crank and crank-pin turned by said handle and operatively connected to said rack whereby turning of the handle in one direction reciprocates the rack and oscillates said elements, a blade-holder, coacting means between said rack and blade-holder to cause the former through the latter to hold the blade alternately against the sharpening elements, and means to shift the position of the blade-holder at each change of direction of rotation of the elements so that the rack may correctly engage it to press the blade against the proper element, substantially as described.
40. 10. In a sharpening appliance of the character described, the combination of three sharpening elements, a plurality of blade-holders each between a pair of said sharpening elements, a handle, and means actuated by said handle when the latter is rotated in a single direction to oscillate said elements and shift the blade-holders to alternately apply one side of each blade-edge to the middle one of the elements when the latter are rotating in one direction and to apply the opposite sides of such blade-edges to the companion elements during the reverse rotation of said elements, substantially as described.
45. 11. In a sharpening appliance of the character described, the combination of a pair of sharpening elements, a pivoted blade-holder having a tapered rider, a reciprocatory rack having a track adapted to cooperate with said rider, a handle adapted to be

rotated in a single direction only, an operative connection between said handle and rack to reciprocate the latter, gears for said elements meshing with the teeth of said rack to oscillate the elements during the reciprocation of the rack, a spring mounted to swing with said blade-holder, and abutments with which said spring coöperates to shift the rider after leaving the rack-track preliminary to the track again engaging the rider

during the reverse movement of the rack, substantially as described.

In witness whereof, I hereunto subscribe my name this 19th day of March, A. D. 1915.

CHARLES RAUCH.
